UNITED STATES PATENT OFFICE.

CHARLES ZEUNER, OF CINCINNATI, OHIO, ASSIGNOR TO INNES & MAGILL, OF SAME PLACE.

DESIGN FOR A GRATE-FRONT.

Specification forming part of Design No. 5,265, dated September 12, 1871.

To all whom it may concern:

Be it known that I, CHARLES ZEUNER, of Cincinnati, Hamilton county, Ohio, have invented and produced a new and original Design for a Summer-Front for Grates, and of which the following is a specification:

The nature of my design is fully represented in the accompanying photographic illustration, to which reference is made.

I claim as my invention—

1. The design for the central ornament A, as herein shown.
2. The ornamental open-work B, as herein shown.
3. The ornamental open-work C, as herein shown.

4. The border D with its ornaments E, when shaped and arranged as shown.

5. The border F, shaped and arranged as herein shown.

6. The ornaments G, as herein shown.

7. The combination of the central ornament A, ornamental open-work B and C, borders D, E, and F, and ornaments G H, when arranged with relation to one another, as herein shown.

In testimony of which invention I hereunto set my hand.

CHARLES ZEUNER.
